UNITED STATES PATENT OFFICE.

ANNA LEBRETON AND ERNEST TALBOT, OF SEATTLE, WASHINGTON.

STREET INDICATOR.

Application filed November 21, 1921. Serial No. 516,790.

To all whom it may concern:

Be it known that we, ANNA LEBRETON, a citizen of France, and ERNEST TALBOT, a citizen of the United States, residing at Seattle, in the county of King and State of Washington, have invented certain new and useful Improvements in Street Indicators, of which the following is a specification.

This invention relates to apparatus for indicating the names of street intersections, stations, etc., to passengers when traveling in railway cars.

The object of the invention is the provision of apparatus of this character which is of simple and durable construction, automatic in operation, and one which will prove of great convenience to the traveling public.

With these and other ends in view, the invention consists in the novel construction, adaptation and combination of parts herein after described and claimed.

In the accompanying drawings—

Figure 1 is a view in front elevation of the street indication means, and the mechanism 25 for operating the same, with the containing case shown in section. Fig. 2 is a sectional view taken substantially on broken line 2—2 of Fig. 1. Fig. 3 is a view partly in side elevation and partly in longitudinal vertical 30 section, showing portions of a railway car, a track rail therefor, and the preferred means for actuating the street indicating mechanism. Fig. 4 is a fragmentary plan of the track rail and actuator shown in Fig. 3. Fig. 35 5 is a detail sectional view through 5—5 in Fig. 4. Fig. 6 is a fragmentary sectional view through 6—6 of Fig. 2.

In said drawings, the numeral 7 represents a casing rigidly secured at a conspicuous place in a railway car and having a sight aperture 8 in its front wall. Provided within the casing 7 is a pair of spools 9 and 10 disposed one above the other and about which is wound a webbing W having marked thereon the names of streets, such as 12 for example, or other information or advertising matter which, in the operation of the apparatus are successively presented at the sight aperture 8.

The spools 9 and 10 are rigidly mounted on horizontal shafts 9¹ and 10¹ which are journaled in bearing boxes provided in bracket supports 11; Fig. 1; secured to the casing.

Keyed or otherwise secured to the respective shafts are wheels 12 and 12¹ preferably

provided with peripheral grooves as indicated by 13 in Fig. 6.

Rotatably mounted upon said wheels are rings 14 and 14¹, respectively, from which 60 extend bifurcated arms 15 and 15¹ toward the back of the casing.

Said rings are provided with substantially triangular shaped recesses 16 and 16¹ extending from the inner peripheries of the 65 rings and disposed in approximately the positions in which they are represented in Fig. 2.

Provided within said recesses are rollers 17 and 17¹ provided with axles such as 18 70 in Fig. 6.

Rotatable upon said shafts at opposite sides of the respective wheels are cams 19 and 19¹ having peripheral surfaces *a* and *b* concentric of the respective shaft axes and of different radial distances therefrom; that is to say—the arcs *a* and *b* are respectively inside and outside of the orbits of the axles of the rollers 17 and 17¹ when the latter are in position to couple the rings 14 and 14¹ to 80 the wheels 12 and 12¹ for imparting rotary motion thereto.

Each pair of cams is provided with arms 20 which are connected by a link 21 which, in turn, is connected by a rod 23 with a stud 85 22 (Fig. 1) movable in a slot 24 in the adjacent side wall of the casing. 25 represents an internally threaded knob engaging screw threads provided on the stud 22 whereby the latter is clamped in adjusted positions to the 90 casing. By suitably raising or lowering the knob 25 the cams 19 and 19¹ are simultaneously regulated to render the rollers in one of said rings selectively inoperative to transmit motion therefrom through the associated 95 wheel to the respective spool.

Extending between the bifurcations of both of the arms 15 and 15¹ is a substantially vertical rod 26 having an adjustable collar 27 engageable with the upper side of arm 15 100 and a second collar 27¹ located to engage the other arm 15¹ from below to impart rotative movements to the rings 14 and 14¹ for transmitting motion through the medium of rollers 17 and 17¹ and wheels 12 and 12¹ to the 105 respective spools.

28 represent springs acting counter to the rod 26 to effect retractile rotative movements to the rings 14 and 14¹ after the successive actions of the rod collars 27 and 27¹.

Referring now to Figs. 3 and 4, the rod 26 is shown as connected below the car body,

indicated by 29, to the longer arm 30 of a lever whose shorter arm 30¹ is connected by a link 31 to the longer arm 32 of a second lever. These levers are respectively fulcrumed at 33 and 34 to a frame 35 depending from the car body, said frame being provided with a guide 36 for a vertically arranged bar 37 which is pivotally connected at 38 to the shorter arm 32¹ of the second named lever.

The lower end of the bar 37 is provided with a relatively large head 39 which is desirably equipped with a shoe 39¹ of an elastic material.

Between said head and the guide 36 is provided a spring 40 to yieldingly retain the bar 37 in its lowermost position which is limited by a stop 37¹ on the bar encountering the guide 36. For raising the rod 26 for actuating the mechanism in the casing to progressively move the web W, an elevating device is provided along one side of a track rail, as 42, in proximity of each of the stations or stopping places whereas a name or legend on the web is to be displaced by another.

As illustrated in Figs. 3, 4 and 5 said elevating device comprises a lever 43 provided in a housing 44 secured to said rail.

This elevating lever is fulcrumed to the housing 44 by means of a pin or bolt 45 and has a curved arm 43¹, as shown in Fig. 3, to be engaged by and depressed by the flanges, as 47, of the car wheels 48 traveling upon the track rail 42, whereby the other arm 43² of the referred to lever will be swung upwardly to effect the elevation of the bar 37 and rod 26 for operating the apparatus. 49 represents a spring acting to retain the lever 43 in a position clear of traffic.

Normally the rod 26 will be in the position indicated by dotted lines 26^a in Fig. 3 with respect to the bar 37 so that when the bar is urged upwardly by the elevating lever 43 the rod will be directly raised by the bar to thereby overcome the static inertia of the rod. After the rod has been thus started in an upward movement the levers 32-32¹ and 30-30¹ are caused to act to complete such movement of the rod and by reason of the character and arrangement of the levers above referred to, the travel of the rod is accelerated and amplified in comparison of the uplift of the bar 37.

The return or downward movement of the rod is by preference accomplished by the action of gravity.

With the cams 19 and 19¹ occupying the relative positions with respect to the rollers 17 and 17¹ in which they are illustrated in Fig. 2, the ring 14¹ is rendered inoperative, while the ring 14 is operable by collar 27 in the downward successive strokes of the rod 26 to impart through the associated wheel 12 rotary impulses to the spool 9 whereby

the web 11 is shifted to indicate the occurrences of the streets or stations.

This action occurs repeatedly during the travel of the car in a direction indicated by arrow in Fig. 3.

When the car is to travel in the opposite direction, the attendant pushes the knob 25 upwardly thereby regulating the cams 19 and 19¹ to render the rollers of the ring 14 idle and those of the ring 14¹ operative to enable the rod 26 to impel the spool 10 to suitably shift the web W.

Supplementary to or in lieu of the actuating mechanism illustrated in Fig. 3, electrical means may be employed, if desired, such means comprising a solenoid winding indicated by dotted lines 50 in Figs. 1 and 2 surrounding the rod 26 and included in an electric circuit, not shown, which is energized by spaced contacts provided on the track or trolley wire. When the solenoid winding is energized the ensuing magnetic power of the solenoid acts to elevate the rod 26 which serves as the armature or core therefor as will be understood.

While we have described the preferred embodiment of the invention, changes in the structural details thereof may obviously be made within the scope of the appended claims.

What we claim, is,—

1. In a railway car, the combination with a web having street indicating names thereon, spools for said web, shafts for said spools, a reciprocatory rod, operative connections between said rod and the respective shafts and actuated by the alternate strokes of said rod for turning the spools in opposite rotary directions, and regulating devices to render said connections temporarily inoperative with respect to either of said spools selectively, of means for effecting the reciprocation of said rod, said means comprising a frame secured to the car body and provided with a guideway, a bar movable axially in said guideway and arranged to normally support said rod, levers operatively connecting said bar to the rod, a lever provided on the railway track and arranged to be influenced by the car wheels whereby said last named lever is influenced to cause said bar to elevate the rod through the instrumentality of the first named levers, and a spring to return the bar and rod to their lowermost positions.

2. In apparatus of the character described, the combination of a pair of spools, a web having street indicating names thereon, shafts for said spools, wheels rigidly mounted on the respective shafts, rings mounted upon said wheels, said rings being provided in their inner peripheries with substantially triangular recesses, rollers provided in said recesses for rotatively coupling the rings to the associated wheels, cams provided upon

the respective shafts, means for adjustably moving said cams in unison whereby the rollers in one of said rings and the rollers in the other of the rings are affected to render the rings operative to transmit rotary impulses to either of said wheels for operating the spools selectively, and means for imparting rotary movements to both of said rings intermittently.

10 3. In apparatus of the character described, the combination with the web, spools therefore, and shafts for said spools, of wheels rigidly mounted on the respective shafts, rings mounted upon said wheels, said rings being provided with arm elements, rollers

interposed between the complementary wheels and rings for rotatively coupling the same together, means for rendering said rollers inoperative to couple the rings to either of said wheels selectively, and means 20 engageable with the arm elements of said rings for imparting reciprocatory rotary movements thereto.

Signed at Seattle, Washington, this 10th day of November, 1921.

ANNA LEBRETON.
ERNEST TALBOT.
